UNITED STATES PATENT OFFICE.

EDMUND P. KINNE, OF ALLIANCE, OHIO, ASSIGNOR TO AMERICAN STEEL FOUNDRIES,
OF NEW YORK, N. Y., A CORPORATION OF NEW JERSEY.

PILOT-BEAM.

1,072,125.

Specification of Letters Patent. Patented Sept. 2, 1913.

Application filed January 30, 1913. Serial No. 745,184.

To all whom it may concern:

Be it known that I, EDMUND P. KINNE, a citizen of the United States, and resident of Alliance, in the county of Stark and State of Ohio, have invented certain new and useful Improvements in Pilot-Beams, of which the following is a specification.

My invention relates to the beam or end casting applied to the pilot end of a locomotive and has particular reference to a novel integral structure for use in connection therewith.

The pilot ends of locomotives particularly such locomotives as are used in switching and freight service, receive a large share of the stresses due to the fact that cars are attached to either end of the locomotive as occasion requires. It thus follows that the beam or end casting which carries the usual coupler, is subjected to severe strains both in pulling and buffing which strains, if not properly applied, lessen the stability of the engine and damage the front trucks and the king-bolt connection to the engine saddle.

I have designed and show in the accompanying drawings, a pilot beam which is extremely rigid, which connects directly with the king-bolt and which provides for a very necessary addition to the ordinary equipment, a draft rigging housing. In connection with the draft rigging housing I have arranged for the application of the rigging and coupler shank from the face of the beam. This is essential in view of the fact that the rigging could not be applied from beneath as is common to freight cars. This is accomplished by the use of a very rigid U-shaped key the two legs of which, when the key is in place, project from the inside lateral edges of the draw-bar opening and prevent the withdrawal of the draft rigging without removal of the key.

It will be understood that the car coupler is suitably connected to the draft rigging, the U-shaped key being contacted by the edges of the front follower of the draft rigging. The specific construction referred to is shown in my co-pending application, Serial No. 735,226.

The invention will be more readily understood by reference to the accompanying drawings, wherein—

Figure 1 is a plan view of a pilot beam constructed in accordance with my invention; Fig. 2 is a section on the line 2—2 of

Fig. 1, and Fig. 3 is a front elevation with the ends of the beam broken away.

Referring more particularly to the drawings it will be seen that the construction includes a cross beam 10, which may be of any desired configuration but is preferably hollow as shown. Projecting rearwardly from this beam is an integral structure 11, having transverse strengthening ribs 12, diagonal ribs 13 and marginal ribs or flanges 14. A king-bolt opening 15, properly reinforced, extends through the structure 11, and provides for the connection of the beam to the engine truck and saddle. Formed within the end beam 10 and the rearwardly projecting structure 11, is a recess 16, the only entrance to which is through the face of the beam 10. Surrounding the opening to the recess 16 is a body of metal 17, 18, 18 at the top and sides thereof. A vertical opening 19 is provided to the rear of the rib 17, this opening extending throughout the height of the beam 10 and forming oppositely facing grooves 20, shown in Fig. 2. Within these grooves 20 I may mount a U-shaped key having depending legs 21 and a top cross bar 22, the cross bar lying behind the metal structure 17. The outer edges of the legs 21 are seated in the vertical grooves 20, the inner edges 25 projecting into the mouth of the recess 16. It will be seen that the metal structure is so arranged that it is extremely rigid, provision is made for the accommodation of a draft gear and the shank of a coupler, and the beam is directly connected through the king-bolt to the frame of the engine. The parts are suitably ribbed and reinforced as required and as found necessary in practice.

Although the structure is shown as one integral casting, it will be understood that portions of the end beam may be formed separately and united by riveting or bolting if found necessary or desirable. Also, that other modifications may be made all of which are within the spirit of my invention.

I claim:

1. A locomotive pilot beam, comprising a hollow beam having a rearward projection provided with a king-bolt opening, said rearward projection and said beam having a recess the entrance to which is through the face of the beam, within which a draft gear may be accommodated, substantially as described.

2. A locomotive pilot beam, comprising a hollow beam having a rearward projection provided with a king-bolt opening, the parts all being cast integral, said structure being provided with a draft rigging recess the opening to which is through the face of the beam, substantially as described.

3. A locomotive pilot beam, comprising an end beam having a rearward projection provided with a king-bolt opening, said

beam and said rearward projection having a draft rigging recess, the entrance to which is through the face of the beam, said beam having vertical key-ways near the mouth of the recess, substantially as described.

EDMUND P. KINNE.
